UNITED STATES PATENT OFFICE

FRANK A. FAHRENWALD, OF CHICAGO, ILLINOIS

FURNACE

Application filed January 18, 1927, Serial No. 161,855. Renewed January 23, 1929.

This invention relates to furnaces and especially to those of the type having internal mechanical conveyors for passing metallic articles through a heated chamber for heat treating purposes, as for example in annealing sheet steel. The objects of the invention are the provision of new, improved, and simplified means for conserving heat and maintaining within the furnace chamber an atmosphere of the desired chemical composition.

In the drawings I have shown a specimen furnace embodying my improvements. Fig. 1 is a longitudinal section, Fig. 2 an end elevation, Fig. 3 a transverse section, Fig. 4 a detail view of a preferred form of roll; and Figs. 5 and 6 illustrate different curves defined by the rolls.

The furnace comprises a floor 1, end walls 2, side walls 3, and an imperforate roof 4, all made of thick, refractory heat insulating material. I have not illustrated the metallic frame work usually employed for strengthening purposes. This is presupposed. Formed in the side walls are openings 5, 5, receiving the ends of horizontal rolls 6. I have illustrated the hot-type of roll constructed as set forth in my application filed October 12, 1925, Serial No. 61,989, namely: rolls made of high temperature alloy and so designed as to run, without local cooling, at any temperature up to about 2000° F. However the present furnace is not restricted to this type of roll.

These rolls are not located in a single plane, but higher inside the body of the furnace than they are adjacent the two ends thereof. The end walls are provided with slots 7 for the ingress and egress of the sheets or other material. Outside of these slots suitable conveyor rolls 8, 8 are provided which deliver and remove the material. Inside the furnace the rolls 6, 6 are elevated gradually from each end above the level of the slots 7, 7. The amount of such elevation and the conformation of the surface thus produced is not important, provided only that the changes in direction be nowhere too abrupt. The curve defined by the rolls may either be a continuous

as shown in Fig. 6. The roof of the furnace is domed or crowned correspondingly and both roof and walls are made without openings so as to produce a kind of gas bell.

The important feature is that most of this curve lies above the level of the slots 7, 7 so that the gases inside the furnace, owing to their decreased density due to their high temperature are trapped therein and neither escape nor admixture can occur provided the side walls are kept tight. This is not difficult to accomplish since the only necessary apertures therein are the apertures 5 for the rolls and these can be packed by the use of cover plates 10 having some kind of soft packing 11 therein like asbestos or magnesia. It will be remembered that the speed of the rolls is very slow and the gas pressure very low.

I do not limit myself to roll type conveyors nor when rolls are used do I limit myself to any one type or shape of roll. I prefer the roll type furnace using non-cooled rolls because of its simplicity and economy but my invention does not depend thereon. I have shown disk-type rolls in Figs. 3 and 4 because of the fact that many prefer them for sheet furnaces, but plain cylindrical rolls in Fig. 1 which can also be used for sheets and are preferable for bars, pallets, and odd shapes. I do not limit myself to any one kind of heating although I prefer electrical heating for which purpose I have shown resistance elements 12, 12 in Fig. 4 located above and below the rolls. As this type of heating requires no gas-flow it is easier to maintain a uniform chemical condition inside the furnace than with a full fired furnace, and the economy of hot gas produced by the shape of the furnace enables electricity to be used economically. Indeed with a proper insulation of the furnace walls and the use of non-cooled rolls the heat consumption becomes very nearly proportional to the tonnage of material operated on, with only a small heat loss. No doors or other closures are required for the slots 7 although their unnecessary or obstructive use does not serve to distinguish from my invention.

Having thus described my invention what I claim is:—

1. A furnace of the character described comprising, in combination, a chambered structure of refractory material having ingress and egress openings, conveyor rolls in said furnace, said rolls having axial extensions which traverse apertures formed therefor in the side wall of said chamber structure, said rolls constituting a mechanical conveyor, portions of said conveyor inside the furnace chamber being elevated above the level of said openings and the roof and walls of said furnace being substantially gas-tight, and means preventing escape of hot gases through the apertures around said rolls.
- 15 2. A furnace of the character described comprising, in combination, an elongated chambered structure of refractory material having ingress and egress openings at opposite ends, a mechanical conveyor extending through said furnace from a point outside of said ingress opening to a point outside of said egress opening, said conveyor comprising a series of parallel horizontal rolls, certain of the rolls inside the furnace chamber being elevated above the level of said openings, said rolls having axial extensions which traverse apertures with which the side walls of said furnace are provided, and means preventing escape of hot gases through said apertures.
- 30

In testimony whereof I hereunto affix my signature.

FRANK A. FAHRENWALD.
